FISHING LURE

George E. Elrod and Vern E. Wood, Tucson, Ariz.

Application October 30, 1956, Serial No. 43,583

Term of patent 14 years

(Cl. D31—4)

Fig. 1

Fig. 2

Fig. 3

Figure 1 is a top perspective view of a fishing lure showing our new design;

Figure 2 is a side elevational view thereof; and

Figure 3 is a front end elevational view of the same.

The dominant features of the design reside in the portions shown in full lines.

We claim:

The ornamental design for a fishing lure, as shown and described.
